UNITED STATES PATENT OFFICE.

KAUFMANN KAUFMANN, OF NEW YORK, N. Y.

DESIGN FOR A VEST-CHAIN LOCK.

Specification forming part of Design No. 5,574, dated March 5, 1872.

Specification describing a new and original Design for a Vest-Chain Lock, invented by KAUFMANN KAUFMANN, of the city of New York, in the county and State of New York.

The drawing represents a perspective view of my new design for a vest-chain lock.

This invention relates to a new watch-chain fastener, made in imitation of a padlock, and known as a vest-chain lock; and consists in making the body of the lock in form of a key-stone, narrower at the lower than at the upper

end, as shown. The face of the key-stone lock may bear suitable ornaments, masonic inscriptions, or other characters.

I claim as my invention—

The design for the key-stone vest-chain lock, as shown.

K. KAUFMANN.
